UNITED STATES PATENT OFFICE.

ALVIN H. MALLISON, OF ARLINGTON, NEW JERSEY, ASSIGNOR TO UNDERWOOD AND UNDERWOOD, OF ARLINGTON, NEW JERSEY, A CORPORATION OF NEW JERSEY.

PHOTOGRAPHIC PRINTING APPARATUS.

No. 862,264.

Specification of Letters Patent.

Patented Aug. 6, 1907.

Application filed October 24, 1904. Serial No. 229,706.

To all whom it may concern:

Be it known that I, ALVIN H. MALLISON, residing at Arlington, in the county of Hudson and State of New Jersey, have invented certain new and useful Improvements in Photographic Printing Apparatus, of which the following is a full, clear, and exact description, such as will enable others skilled in the art to which it appertains to make and use the same.

This invention relates to photographic printing apparatus.

One of the objects thereof is to provide a simple and efficient piece of apparatus whereby a succession of prints can be made from a single negative without the necessity of disturbing either the latter or the source of light to which it is exposed.

Another object is to provide means for holding the sensitized paper firmly against the negative during the operation of printing.

Another object is to provide means in a piece of apparatus of the above type whereby the intensity of the light may be varied and the exposure of the plate thereto may be automatically cut off at the proper time.

Another object is to provide means of the above types which shall be entirely automatic and reliable in action. Other objects will be in part obvious and in part pointed out hereinafter.

The invention accordingly consists in the features of construction, combinations of elements and arrangement of parts which will be exemplified in the apparatus herein described and the scope of the application of which will be indicated in the claims at the end of this description.

In the accompanying drawings wherein are shown two of various possible embodiments of my invention, Figure 1 is a side elevation of the same. Fig. 2 is an end elevation of the same. Fig. 3 is a plan. Fig. 4 is an enlarged section taken on the line 4—4 of Fig. 1. Fig. 5 is a side elevation of portions of the above embodiment on an enlarged scale, certain parts being broken away. Fig. 6 is a plan of certain parts shown in Fig. 5, certain parts thereof being broken away. Fig. 7 is a sectional elevation taken centrally through a portion of the apparatus. Fig. 8 is an end elevation on an enlarged scale of a casing and associated parts taken in the direction indicated by the arrow in Fig. 1. Fig. 9 is an enlarged section taken centrally through a portion of the casing substantially on the line 9—9 of Fig. 1. Fig. 10 is a portion of a sensitized strip showing holes perforated for the purpose of gripping the same. Fig. 11 is an enlarged vertical section showing a slightly different embodiment of certain features of my invention. Fig. 12 is a horizontal section taken on the line 12—12 of Fig. 11.

Similar reference characters refer to similar parts throughout the several views.

In order to render clearer the general nature of my invention, it may here be noted that it is often desirable to make a succession of prints from a single negative, as, for example, in the case of making photographic prints for use in connection with a stereoscope. On account of the small selling price of such prints, it is of the utmost importance that the apparatus whereby they are formed be as nearly automatic in action as possible and that the interval of time between successive exposures be as small as is consistent with the general efficiency of the apparatus. In this way the cost of production is reduced by means of eliminating the necessity for manual labor and cutting short the time required to form the print. It is also highly desirable in apparatus of this type that the action of the several parts be positive, and this is of especial importance with regard to the means whereby the sensitized paper is moved with relation to the frame, as, if any slipping occurs at this point, the paper is unlikely to be drawn throughout the length of an entire print, and thus the prints are caused to overlap. It is also requisite for the best results that the intensity of the light be adjustable and that the sensitized paper be firmly held against the negative. The above and other advantages are attained in constructions of the nature of that hereinafter described.

Referring now to Fig. 1 of the drawings, 1 and 2 represent uprights connecting which in pairs are the cross pieces 3. Between these cross pieces is stretched a longitudinal support 4 adapted to stiffen the frame, and mounted upon the uprights adjacent their upper ends is a casing 5. Within this casing is mounted a source of light which, in this case, is shown as an incandescent electric lamp. By the term "source of light" as used throughout this specification and in the following claims is intended any member or instrument adapted to emit light of an appreciable intensity irrespective of the agent whereby the light is produced, and the term is also used herein in a very broad sense to designate any member which is designed for and is capable of emitting light upon being supplied with the proper current or fuel. Lamp 6 is mounted upon a carriage 7 which is slidably within grooves 8 for a purpose herein-after explained.

At one end of the casing 5 is a negative holding frame 9 which in this case, comprises the tapering side walls 10 and a gripping member 11 which is slidably mounted in guide 12 and is pressed against the rear side of the negative 9 by means of a spring 13.

Pivotedly mounted in front of the tapering walls 10 is a hinged shutter 14, fixed upon which is a short lever arm 15. The latter arm is connected by means of a link 16 with a lever 17 pivoted at 18 upon a supporting block 19 mounted upon the casing. The remaining end of this lever is pivotally connected with a sliding plate 20 the end of which lies within the path

of travel of a cam 21 fixed upon a shaft 22 which is journaled within upright members 23 secured to the frame. The sliding plate 20, the range of movement of which is limited as by slots 24 and pins 25, is normally held 5 in an advanced position corresponding to an open condition of the shutter by means of a spiral spring 26 preferably secured at one end to the pivotal joint between link 16 and lever 17, and having its remaining end fixed to the frame. The chance of entry of light 10 between the shutter 14 and the tapering walls 10 at the top and bottom thereof is eliminated by means of beveled wings 27 secured to the shutter. In this manner, cam 21 forcing the slide 20 to the rear, will hold the shutter in closed condition, but upon the 15 slide being released, spring 26 will open the shutter.

Driven from a sprocket wheel 28 upon shaft 22 which in turn is driven from any desired source of power, as by means of chain 29, is a sprocket wheel 30 fixed upon a shaft 31 which is journaled within suitable bearings in upright members 23. Upon the latter shaft is a cam 32 adapted to actuate an arm 33 through a set screw 34. Arm 33 is drawn in the direction of the cam by means of a spring 35. 36 is a slide which is adapted to reciprocate within a guide 37 secured to 25 the side of the casing. Fixed upon slide 36 is an arm 38 having secured thereto a felt-lined member 39 which is normally forced by spring 35 in the direction of the negative for a purpose hereinafter explained.

At the upper extremity of uprights 1 is mounted a 30 supply roll 40 upon which is wound a strip of sensitized paper 41 which is directed by means of guide 42 so as to pass the negative, as is clearly shown in Fig. 1 of the drawings. Strip 41 passes from the rear surface of the negative to a receiving roller 43 journaled in 35 brackets 44 mounted upon the uprights 1. The strip is maintained under tension by means of this roller which is provided with a pulley 45 connected with a driving pulley 46 upon the shaft 22 by means of a small belt 47. In this manner the roller has a tendency to rotate in a direction tending to take up any slack in the strip 41, the belt 47 slipping upon its pulleys upon the strip being thus drawn taut. The desired intermittent movement of strip 41 is attained by 40 means of the following mechanism.

45 A slide 48 is adapted to reciprocate within suitable grooves in uprights 1 and normally held in its uppermost position by means of a counterbalance weight 49, the cord 50 of which passes over a suitable pulley 51. Slide 48 which, together with the associated parts 50 forms what may be termed a "clamp", has positioned therein a member 52 within the recesses 53 in which the strip 41 is guided. Member 52 is provided with perforations 54 registering with the larger perforations 55 in the backing of the slide and a movable bar 56 bearing perforating pins 57 is slidably mounted upon the bolts 58. Secured to bar 56 at its central portion, is a felt-covered plate 59 adapted to engage the strip when the bar is thrust in its innermost or operative position and thus aid in gripping the same. The desired movement of bar 56 is brought about by means 55 of a sliding rod 60 mounted upon support 4, and provided with a depending arm 61, upon which is fixed a pin 62, and an upwardly projecting arm 63. Rod 60 is actuated by means of a pin 64 fixed upon a crank disk 65 on shaft 31, the pin engaging the upwardly

projecting arms 66 and 67 successively and thus causing an intermittent reciprocating movement of the rod. Pin 64 is so positioned and shaft 31 so driven as to cause the rod to move toward the slide when the latter is in its uppermost position and by means of engaging the movable bar 56 thrust the pins 57 through the strip and grip the same by means of member 59. Upon the slide reaching its lowermost position, the pin 62 enters a notch 68 cut in the lower surface of bar 56 and the rod 60 thus has connection with the bar, 70 and its movement is so controlled as to withdraw the same and release the strip when the parts reach this condition. The lower end of slide 48 is connected by means of a slotted link 69 with a crank 70 fixed upon the shaft 71, which is driven as by means of sprocket 75 chain 72 and sprocket 73 from shaft 31.

It may here be noted that the word "paper" is used in a broad sense throughout this specification and in the following claims, as comprehending any pliable member adapted to be sensitized by the application 80 of a suitable emulsion so as to be affected by exposure to light. It may here be noted that the downwardly extending arm 61 may be provided with a removable knife for the purpose of cutting the roll at any desired point.

90 The operation of the above described embodiment of my invention is as follows:—Assuming the parts to be in the position shown in Fig. 1 of the drawings and the sensitized paper from the roll 40 to be suitably guided past a negative within the negative holder, and 95 bearing in mind that the clamping member 11 whereby the negative is held in position is continually operating unless released by hand, as for the purpose of changing the negative, the parts are so constructed and arranged as to permit the spring 35 to cause member 39 to press 100 the paper firmly against the rear surface of the negative and the spring 26 to hold the shutter in open position. Just before the exposure has been completed, the length of which may be determined by means of varying the speed of the machine or adjusting the position 105 of the source of light, the paper is clamped by the felt-covered plate 59 and holes are punched through the paper by the pins 57 carried by the bar 56, said bar being forced forward by the upwardly projecting arm 110 63 of the rod 60, said arm 63 being moved in a forward direction by the pin 64 on the crank disk 65 engaging the upwardly projecting arm 66. After the paper has been exposed under the negative the determined length of time, the shutter 14 is closed, the proper closing movement being transmitted by the cam 21 through the 115 slide 20, lever 17, link 16 and arm 15. As soon as the shutter is closed, the felt-lined member 39 is released from the paper by means of cam 32 engaging set-screw 34 in arm 33, which is connected to the member 39 through the slide 36 and arm 38. At this time the 120 slowly moving crank 70 has reached the lower end of the slot within link 69 and thus draws the entire "clamp" downwardly against the force of weight 49. In this manner, a fresh surface of sensitized paper is brought opposite the negative, and cam 32 immediately thereafter releases the spring 35, which draws the fresh surface of paper against the negative as above described. This is instantly followed by the opening 125 of the shutter 14, spring 26 being released by cam 21, and a second exposure is begun. At this point the pin 130

63 64 engages arm 67 upon rod 60, and pin 62 being positioned within the recess 68, the movable bar 56 is withdrawn and the strip released. Crank 70 is now at its lower extreme of its path of travel and an upward 5 movement of the slide 48 under the influence of counter-balance 49 is immediately begun. The above series of operations may be repeated indefinitely and at any desired speed, depending mainly upon the length of exposure which it is desired to give the print.

10 It will thus be seen that I have provided a simple, inexpensive and durable piece of apparatus whereby a succession of prints may be made from a single negative, without the need for supervision or manual labor. The gripping mechanism is so positive in action as 15 practically to obviate any chance of slipping, and an exactly uniform succession of movements of the strip is thus obtained. The several parts, moreover, are readily accessible and the negative may be changed with a minimum of effort. Also, suitable adjustments 20 are provided, as above indicated, so as to cause the several movements to take place at exactly the desired time, and to vary the intensity of the source of light so as to suit the character of the negative used.

In Figs. 11 and 12 is shown a slightly different embodiment of certain features of my invention in which the arm 61 is provided with a depending extension 74 to which is adjustably secured a cutting blade 75 by means of the screw 76. A cross piece 77 is mounted upon uprights 1 and has secured thereto a blade 78 by means of a nut 79. Blades 75 and 78 are adapted to co-act one with another and the strip 41 is thus cut into sections exactly equal in length, each section corresponding to a single print. These sections may be received in any desired manner, as by means of a suitable 35 chute and basket. The advantages of the last described embodiment for the purpose of automatically separating the several prints should be largely obvious. As many changes could be made in the above construction and many apparently widely different 40 embodiments of my invention could be made without departing from the scope thereof, I intend that all matter contained in the above description or shown in the accompanying drawings shall be interpreted as illustrative and not in a limiting sense. I desire it also

45 to be understood that the language used in the following claims is intended to cover all of the generic and specific features of the invention herein described and all statements of the scope of the invention, which, as a matter of language, might be said to fall therebetween.

50 Having described my invention, what I claim as new and desire to secure by Letters Patent is:—

1. In apparatus of the class described, a casing, means adapted to hold a negative at one end of said casing, a source of light adjustably supported within said casing, 55 means adapted to place successively, portions of paper opposite said negative and then to release the paper a shutter adapted to be interposed between said source of light and said negative holding means, and positively acting automatic means adapted to interpose said shutter.

60 2. In apparatus of the class described, a casing, means adapted to hold a negative at one end of said casing, a source of light supported within said casing, means adapted to place successively, portions of paper opposite said negative and then to release the paper means adapted to 65 press the paper in the direction of said negative holding means, and positively acting automatic means adapted to retract the same.

3. In apparatus of the class described, a casing, means

adapted to hold a negative at one end of said casing, means adapted to support a source of light within said casing, means adapted to place successively, portions of paper opposite said negative and then to release the paper a shutter, automatic means for interposing said shutter between said source of light and said negative holding means, means adapted to press the paper in the direction of said negative holding means, and positively acting automatic means for retracting the same.

4. In apparatus of the class described, a source of light, means adapted to hold a negative exposed to said source of light, means adapted to place successively, portions of paper opposite said negative and then to release the paper a shutter, automatic means for interposing the same between said source of light and said negative holding means, means adapted to press the paper in the direction of said negative holding means, and positively acting automatic means for retracting the same.

5. In apparatus of the class described, a source of light, a negative holding frame mounted adjacent the same, means adapted to place successively, portions of paper opposite said negative and then to release the paper a movable member adapted to press the paper against the negative, a spring connected with said member, and automatic power-actuated means adapted to overcome said spring and retract said member.

6. In apparatus of the class described, a source of light, negative holding means, means adapted to place successively, portions of paper opposite said negative and then to release the paper a hinged shutter adapted to swing into a position between the negative and said source of light, automatic power-actuated means adapted to swing said shutter into closed position, and a spring connected with and adapted to open the same.

7. In apparatus of the class described, a source of light, negative holding means, a hinged shutter adapted to swing into a position between the negative and said source of light, automatic power-actuated means adapted to close the same, spring-actuated retracting means connected with said shutter, a member adapted to exert a pressure against the negative in the direction of said source of light, a spring having an operative connection therewith, and automatic power-actuated means adapted to overcome said spring and retract said member.

8. In apparatus of the class described, a casing, a source of light adjustably positioned therein, negative holding means at one end of said casing, a spring-retracted hinged shutter adapted to swing into a position between the negative and said source of light, automatic power-actuated means adapted to close said shutter, a member adapted to exert a pressure against the negative substantially in the direction of said source of light, a spring connected therewith and tending to hold the same in operative position, and automatic power-actuated means adapted to overcome said spring and retract said member.

9. In apparatus of the class described, a source of light, negative holding means, and means adapted automatically to place successively a series of portions of paper opposite said negative holding means and exposed to said source of light and then to release the paper.

10. In apparatus of the class described, a source of light, negative holding means, and automatic means adapted to place successively and periodically a series of portions of paper opposite said negative holding means and exposed to said source of light and then to release the paper.

11. In apparatus of the class described, a source of light, negative holding means, means adapted to hold a strip of paper, and automatic means adapted successively to place a series of portions of said strip of paper opposite said negative holding means and exposed to said source of light and then to release the paper.

12. In apparatus of the class described, a source of light, negative holding means, means adapted to hold a strip of paper, and means adapted successively to place a series of portions of said strip of paper opposite said negative holding means and exposed to said source of light and then to release the paper.

13. In apparatus of the class described, negative holding means, means adapted to hold a strip of paper; means adapted to guide the strip past the negative, and automatic means adapted to grip and draw said strip of paper

for a predetermined distance with reference to said negative and then to release the paper.

14. In apparatus of the class described, negative holding means, means adapted to hold a strip of paper, means for guiding said strip past the negative, and automatic means adapted positively to grip and draw said strip of paper for a predetermined distance with reference to said negative and then to release the paper.

15. In apparatus of the class described, negative holding means, means adapted to hold a strip of paper, means for guiding said strip past the negative, automatic means adapted positively to grip and draw said strip for a predetermined distance with reference to said negative holding means, and means adapted to release said strip and retract said gripping means.

16. In apparatus of the class described, negative holding means, means adapted to hold a strip of paper, means for guiding said strip past the negative, a clamp about said strip, automatic means adapted to close said clamp and positively grip said strip and to open said clamp and release said strip, and means adapted to impart a reciprocating movement to said clamp.

17. In apparatus of the class described, negative holding means, means adapted to hold a strip of paper, means adapted to guide the strip past said negative holding means, a clamp about said strip provided with a pin, automatic means adapted to close said clamp and thrust said pin through said strip, means adapted to reciprocate said clamping device, and means for withdrawing said pin and releasing said strip operative when said clamping means is at the lower extreme of its path of travel.

18. In apparatus of the class described, negative holding means, means adapted to hold a strip of paper, means adapted to guide said strip past the negative, clamping means about said strip of paper, said clamping means comprising a movable member bearing a plurality of pins, means adapted to reciprocate said clamping means, a slidable member adapted to make operative connection with said movable member when the latter is at each of the extremes of its path of travel, and automatic power-actuated means adapted to actuate said movable member through said slidable member and alternately contract said clamp and thrust said pins therethrough and release said clamp and withdraw said pins.

45 19. In apparatus of the class described, negative holding means, means adapted to hold a strip of paper, means adapted to guide the strip past the negative, clamping means embracing said strip, automatic means adapted alternately to contract and release said clamping means, a slotted link connected with said clamping means, and a revolute member provided with a crank pin positioned within the slot of said link and adapted to impart an intermittent reciprocating movement to said clamping means.

20. In apparatus of the class described, a source of light, a casing within which said source of light is mounted, means adapted to hold a negative at one end of said casing, means adapted to hold a strip of paper, means for guiding the strip past the negative, and automatic means adapted successively to place a series of portions of said strip of paper opposite said negative holding means and exposed to said source of light and then to release the paper.

21. In apparatus of the class described, a source of light, a casing, means adapted to hold a negative at one end of said casing, means adapted to hold a strip of paper, means for guiding the strip past the negative, automatic means adapted successively to place a series of portions of said strip of paper opposite said negative holding means and exposed to said source of light and then to release the paper, and automatic means adapted intermittently to press said strip against the negative.

22. In apparatus of the class described, a casing, a source of light adjustably positioned within said casing, negative holding means at the end of said casing, an automatically actuated shutter adapted to be interposed between said source of light and said negative holding means, an automatically and intermittently actuated member adapted to exert a pressure in the direction of said source of light, means adapted to hold a strip of paper, means for guiding said strip between said member and the

negative, and automatic means adapted positively to grip said strip and draw the same for a predetermined distance with reference to said negative holding means and then to release the same.

23. In combination, a casing, negative holding means at one end thereof, a source of light adjustably positioned within said casing, a movable shutter adapted to be interposed between said source of light and the negative, an automatically actuated member adapted to exert a pressure in the direction of said source of light, means adapted to hold a strip of paper, means for guiding the strip past the negative, a clamp about said strip, and automatic power-actuated means adapted successively to close said shutter, release said pressure applying means, grip said paper, draw said clamp downwardly, reapply said pressure, open said shutter, release said clamp and retract the same.

24. In apparatus of the class described, a casing, a source of light adjustably positioned within said casing, negative holding means at one end thereof, a spring retracted shutter mounted adjacent said negative holding means, automatic power-actuated means for interposing said shutter between said source of light and the negative, a roll adapted to hold a strip of paper, means for guiding said strip past the negative, a spring-pressed member adapted to press said strip against said negative, automatic power-actuated means for retracting the same, a clamping member about said strip, a pin within said clamping member, means adapted to close said clamping member and thrust said pin through said strip, a revolute member, a crank pin thereon, a slotted link connected with said clamping member, said crank pin projecting through the slotted end of said link, and automatic power-actuated means adapted successively to close said clamp and thrust said pin through said strip, move said clamp for a predetermined distance, open said clamp and retract the same.

25. In apparatus of the class described, a frame, a casing mounted thereon, a source of light adjustably positioned within said casing, negative holding means at one end thereof, a spring-retracted hinged shutter adapted to swing into a position between said negative holding means and said source of light, a shaft mounted upon said frame, a cam upon said shaft, a connection between said shutter and said cam whereby said cam is adapted to close said shutter against the force of said spring, a roll adapted to hold a strip of paper, means for guiding the strip past the negative, a spring-pressed slidable member adapted to press said strip against the negative, a second shaft mounted upon said frame, a cam upon said shaft, a connection between said pressure member and said cam whereby said cam is adapted to retract the same, clamping means about said strip comprising a movable member having a plurality of pins, a projection revolute about said second shaft, a slidable member having an operative connection with said projection and adapted to open and close said clamping means, said pins being thrust through said strip when said clamping means is in closed condition, a third shaft mounted upon said frame, a crank upon said shaft, a slotted link between said crank and said clamping means, counter-balancing means adapted to tend to hold said clamping means in its uppermost position, connections between said shafts and connections whereby the same are adapted to be driven from a common source of power.

26. In apparatus of the class described, a source of light, negative holding means, a supply roll adapted to hold a strip of paper, a receiving roll adapted to receive said strip of paper from said supply roll, and automatic means adapted successively to place a series of portions of said strip of paper opposite said negative holding means and exposed to said source of light and then to release the paper.

27. In apparatus of the class described, negative holding means, a supply roll adapted to hold a strip of paper, means adapted to guide the strip past the negative, a receiving roll adapted to receive said strip from said supply roll, means adapted to place said receiving roll under tension, and automatic means adapted to grip and draw said strip of paper for a predetermined distance with reference to said negative.

28. In apparatus of the class described, negative holding means, a supply roll adapted to hold a strip of paper, means for guiding said strip of paper past the negative, a receiving roll adapted to receive said strip from said supply roll, automatic means adapted positively to grip and draw said strip for a predetermined distance with reference to said negative holding means, and means adapted to release said strip and retract said gripping means.
29. In apparatus of the class described, negative holding means, a supply roll adapted to hold a strip of paper, means for guiding said strip past the negative, a receiving roll adapted to receive said paper from said supply roll, a pulley upon said receiving roll, a belt upon said pulley, a clamp about said strip, automatic means adapted to close said clamp and positively grip said strip, and to open said clamp and release said strip, and means adapted to impart a reciprocating movement to said clamp.
30. In apparatus of the class described, negative holding means, a supply roll adapted to hold a strip of paper, means adapted to guide the strip past said negative holding means, a receiving roll adapted to receive said strip, means adapted to maintain said receiving roll under tension, a clamp about said strip provided with a pin, automatic means adapted to close said clamp and thrust said pin through said strip, means adapted to reciprocate said clamping device, and means for withdrawing said pin and releasing said strip when said clamping means is at the lower extreme of its path of travel.
31. In apparatus of the class described, a source of light, a casing, means adapted to hold a negative at one end of said casing, a supply roll adapted to hold a strip of paper, means for guiding the strip past the negative, a receiving roll adapted to receive said strip from said supply roll, automatic means adapted successively to place a series of portions of said strip of paper opposite said holding means and exposed to said source of light and then to release the paper, and automatic means adapted intermittently to press said strip against the negative.
32. In apparatus of the class described, a frame, a casing mounted thereon, a source of light adjustably positioned within said casing, negative holding means at one end thereof, a spring-retracted hinged shutter adapted to swing into a position between said negative holding means and said source of light, a shaft mounted upon said frame, a cam upon said shaft, a connection between said shutter 45 and said cam whereby said cam is adapted to close said shutter against the force of said spring, a roll adapted to hold a strip of paper, means for guiding the strip past the negative, a receiving roll adapted to receive said strip from said first mentioned roll, means for maintaining said 50 receiving roll under tension, a spring-pressed slideable member adapted to press said strip against the negative, a second shaft mounted upon said frame, a cam upon said shaft, a connection between said pressure member and said cam whereby said cam is adapted to retract the same, 55 clamping means about said strip comprising a movable member having a plurality of pins, a projection revoluble about said second mentioned shaft, a slideable member having an operative connection with said projection adapted to open and close said clamping means, said pins being 60 thrust through said strip when said clamping means is in closed condition, a third shaft mounted upon said frame, a crank upon said shaft, a slotted link between said crank and said clamping means, counterbalancing means adapted to tend to hold said clamping means in its uppermost position, connections between said shafts and connections whereby the same are adapted to be driven from a common 65 source of power.

In testimony wherof I affix my signature, in the presence of two witnesses.

ALVIN H. MALLISON.
